PICKER STICK CHECKING APPARATUS**Joseph Rockoff, Dayton, Ohio, assignor to The Dayton Rubber Company, a corporation of Ohio****Application June 19, 1953, Serial No. 362,901****11 Claims. (Cl. 139—161)**

The present invention relates to check straps for looms, and more particularly to check straps for fly shuttle looms which are designed to check rearward motion of the picker stick caused by impact of the shuttle, as well as forward motion of the picker stick after it has thrown the shuttle in its return through the loom. It relates further to checking mechanisms incorporating such check straps.

Straps of this type have previously been made of leather either in the form of a strap having the ends bolted together and to the loom frame to form a loop, or in the form of an endless band which surrounds the stick and is supported by friction fingers which restrict movement of the strap under the impact of the picker stick. Since these straps are subjected to repeated impacts of the rapidly moving picker stick they must have sufficient strength, flexibility, and resilience to provide the necessary restraining action upon the stick without excessive wear and without excessive frictional drag. Furthermore, the strap must not be sensitive to changes in temperature or humidity as is generally the case with leather. In the co-pending application of Henry M. Bacon, Serial No. 75,387, filed February 9, 1949, now U. S. Patent No. 2,698,032, a laminated rubber and fabric check strap construction is described which has been found to possess long life, flexibility, and suitable frictional resistance and resiliency to give satisfactory performance in the checking mechanisms of looms. In the construction of the check strap according to the application referred to, the outer fabric layers have been made of cotton fabric either impregnated or coated with rubber compound. In accordance with applicant's present invention it has been discovered that improved results may be obtained by the use of a particular fabric construction for the inner and outer surface layers of the strap, or in other words, by modifying the nature of the fabric layers which are in contact with the stick and the snubbing or friction fingers in the checking mechanism.

Applicant has discovered that improved performance and life of the check strap are obtained if the outer fabric layers are composed of a nylon fabric or a fabric made of a blend of nylon and cotton fibers. More particularly, applicant has discovered that nylon-cotton blends containing at least about 50 percent nylon and at least about 10 percent cotton, or in other words, containing about 50 percent to 90 percent nylon fibers and about 50 percent to 10 percent cotton fibers are to be preferred. Other fibers such as rayon, Orlon, or the like may be used in admixture with the nylon-cotton blend provided the mixture contains at least 50 percent nylon fibers and 10 percent cotton fibers. The most suitable type of fabric for the proper adhesion described is one in which the threads of which the fabric is composed are made of fibers containing nylon-cut staple fibers. A preferred nylon-cotton blend is one in which fabric is woven with threads composed of nylon-cut staple and cotton fibers in the proportion of about 75

percent nylon and about 25 percent cotton. The fabric is preferably square woven and is applied to the check strap construction on the bias.

Applicant has further discovered that improved performance and life of the check strap may be obtained if the longitudinally extending strength cords which are sometimes included in transverse layers in check strap construction, are also composed of a nylon or nylon-cotton blend similar to that above described.

10 Whether or not the longitudinal strength cords are employed in the strap construction, applicant has discovered that optimum results may be obtained if the outer exposed surfaces of the strap are free from rubber or rubber-like material. This is particularly true where 15 straps of this invention, being built and vulcanized in cylindrical form and tending to assume this cylindrical shape during operation, are employed. As a result of the tendency of the strap to change from the pinched and elongated shape it is forced to assume between the 20 snubbing fingers with which it will operate to the cylindrical shape in which it was built and vulcanized, a radial force is exerted by the outer surface of the strap against the snubbing finger which is contiguous therewith. This force likewise causes a forced contact between the inner 25 surface of the strap and the snubbing fingers contiguous with it. Where a force normal to the contact surface between the strap and the snubbing fingers is thus provided, the checking does not depend so much upon the friction properties of the surface. It has accordingly 30 been found feasible and desirable to keep these outer surfaces free of any frictioning material such as rubber, and this invention provides that the same be made up solely of a nylon containing fabric to achieve still more improved checking properties. In order that the fabric 35 forming these outer surfaces of the strap may be properly adhered and vulcanized to the rest of the strap, it is, of course, permissible to friction the side of the fabric to be placed toward the interior of the strap.

To provide a protective coating for the edges of the 40 check straps which will save them from the deleterious effects of exposure to the atmosphere and abrasive contacts with other straps resulting in the fraying and wearing away of the fabric and cords exposed at these edges but at the same time, will not unduly increase their friction coefficient, the straps of the present invention are 45 provided with a thin film of nylon about their edge surfaces. This coating may be provided in any convenient manner such as by spraying or painting the edges with a nylon solution or dispersion. A fused nylon coating 50 may be conveniently provided where the nylon blend fabric and/or cords are employed as above described, by simply applying sufficient heat to the edges of the strap to fuse the nylon in the fabric exposed to the heated edge. The heat necessary to fuse the nylon in 55 the textile material exposed to the strap edges may be conveniently applied by placing the finally cut strap between heated platens which are maintained at a temperature sufficient to cause fusion of the nylon but which are at the same time not so high as to cause any weakening thereof. Such temperature is preferably just below 60 the melting point of the nylon which will range from 409° F. to 496° F.

It is therefore an object of the present invention to 65 provide an improved check strap construction having increased durability and improved performance.

It is a further object of the present invention to provide an improved check strap construction wherein the strap will have a desired coefficient of friction when used with friction or snubbing fingers.

70 It is yet a further object of the present invention to provide an improved check strap the edges of which will have a desired coefficient of friction when used in

multiple, but will at the same time be protected from the atmosphere and the deteriorating effect of the abrasion resulting from their rubbing together.

It is another object of the present invention to provide a method for the manufacture of the improved check strap herein contained.

It is a still further object of this invention to provide an improved checking mechanism incorporating the check strap of this invention.

The checkstrap construction of the present invention may be further described with reference to the accompanying drawings, in which:

Figure 1 is a view in perspective of an endless, cylindrical check strap of the present invention.

Figure 2 is a cross-sectional view showing the construction of the check strap taken along lines 2-2 of Figure 1.

Figure 3 is an elevational view of a portion of a loom showing the checking mechanism incorporating multiple check straps.

Figure 4 is a plan view in partial cross section of the checking mechanism of Figure 3 taken along the line 4-4 thereof.

In Figure 1, the check strap 10 is shown in the cylindrical form it naturally assumes after having been built and vulcanized while upon a cylindrical mandrel. In practice this strap will be forced to assume a pinched and elongated shape as it is gripped between the snubbing fingers of the checking mechanism in the manner of the strap shown in Figure 4. When the strap is placed in operating position, it will be horizontally disposed so that it will be engaged by the snubbing fingers along the surfaces 12 and 12a, the edge surfaces 11 being exposed to the atmosphere or rubbing contact with other straps of the mechanism. As the strap moves back and forth between the snubbing fingers under the impact of the picker stick, it will tend to return to the cylindrical shape in which it was built and vulcanized; and this tendency has been found to provide a desired forced contact between the strap and the fingers thereby improving the effectiveness of the checking mechanism.

The internal construction of the strap is illustrated in the cross-sectional view shown in Figure 2. The outermost layers 12 and 12a are composed of the previously described nylon or nylon-cotton blend fabric which, as further set forth above, are preferably free from any rubber-like material, on their outer surfaces so that slippage of these surfaces along the snubbing fingers will not be greatly inhibited. Interiorly of these outer fabric layers may be positioned a plurality of inner fabric layers preferably, but not necessarily, composed of the same material as outer layers 12 and 12a. In this preferred embodiment of the present invention these interior fabric layers 13 and 13a are shown to be separated by layers of rubber or rubber-like material such as 14 and 15. These rubber-like layers may be applied separately in the construction of the strap or they may consist simply of skim coating which has been applied to the fabric prior to its being wound about the drum or mandrel in the building process.

At the central portion of the strap between these fabric or alternating fabric and rubber layers is located a layer of longitudinally extending parallel cords 16 which are themselves preferably embedded between cushioning layers of rubber or rubber-like material 17 and 18.

The strap is formed by first preparing a cylindrical sleeve of the desired dimensions made up of the various layers and then by cutting the sleeve into a plurality of bands or straps of the desired width and having a rectangular cross section. In the manufacture of the straps by this method, a drum or mandrel is selected having a diameter conforming to the desired inner diameter of the strap. This mandrel is then wrapped with a layer of the nylon fabric 12a and then with additional layers of fabric 13 and rubber-like material 14. Layer 12a is pref-

erably frictioned or skim coated on one side with a rubber compound and is applied to the mandrel with the rubber coated side up so that the surface in contact with the mandrel does not have a rubber coating thereon. Successive layers of fabric may be impregnated or frictioned on both sides with or without skim coating. Fabric layer 12a is "bias laid" which means that the fabric is cut at an angle or bias to the direction of the threads or cords and is applied to the drum with the threads at an acute angle to the longitudinal axis of the drum. The other fabric layer 13 may be either bias or laid straight.

Over the fabric layer or layers is superimposed a cushioning layer of rubber shown at 17. This layer is composed of unvulcanized compounded rubber and is of a fairly soft stock. Upon this cushioning layer is then wound a layer of cord 16. This cord layer is wound upon the mandrel in the form of a helix and has preferably been preliminarily treated or impregnated to improve its adhesive properties for rubber. This impregnation may be by treatment with rubber latex or rubber solutions or with a resorcinol-formaldehyde-latex composition as commonly used in the treatment of tire cord. The cord is wound spirally around the drum in a continuous manner, and the windings may be contiguous or spaced as desired.

Alternatively, the cord may be applied in the form of a fabric in which parallel cords are held in spaced relationship by means of transverse pick threads. In such case, the cord fabric is coated or embedded with rubber prior to application around the mandrel.

Another cushioning layer of rubber is then applied over the cord layer as shown at 18 in Figure 2. A plurality of fabric layers 13a and rubber layers 15 are then applied over cushioning layer 18 and an outer layer of fabric 12 applied last. The outer layer is a nylon containing fabric similar to layer 12a. Layers 13a may be cotton or nylon. Outer layer 12a is bias laid and layers 13 may be either straight or bias laid.

The assembled laminated layers on the mandrel are now rag wrapped to place the sleeve under pressure in order to obtain a unitary structure after vulcanization. This is accomplished by tightly winding strips of heavy fabric known as rag wrap material, around the assembly. The wrapped drum is then placed in an autoclave where it is vulcanized in the presence of steam in the conventional manner.

The various rubber materials composing the cushioning layers and the fabric coating or impregnating material layers separating these fabrics have been compounded with vulcanizing agents, accelerating agents, pigments, fillers, and the like, as is well known in the art.

After vulcanization the assembly is taken from the autoclave and the wrapping removed. The cylindrical composite sleeve may then be removed from the mandrel and placed upon a cutting drum where it is cut into a plurality of bands or straps of the desired width, being severed circumferentially by knives spaced at the desired distance. The resulting check straps are then removed from the mandrel. As shown in Figure 2, the side edges of the respective layers are exposed by the severing operation.

A preferred check strap construction is as follows:

Inner layer 1 ply square-woven 8 ounce nylon-cotton fabric; 2 ply warp, and 2 ply filler containing nylon-cut staple 75 percent, cotton 25 percent, frictioned with rubber on the inner surface and with the outer surface unrubberized. This fabric is bias cut and bias laid. This layer forms inner layer 11, the outer exposed surface of which is free from rubber. If desired, this layer may be frictioned or skimmed on one side with rubber to promote adhesion to the adjacent fabric layers.

3 plies rubberized square-woven 8 ounce cotton fabric frictioned with neoprene on both sides and skim coated on one and bias laid.

1 ply cushion layer of neoprene

- 1 ply all nylon cord 0.053 gauge
 1 ply cushion layer of neoprene
 3 plies rubberized square-woven 8 ounce cotton fabric
 frictioned on two sides, skim coated on one
 1 outside ply of nylon fabric corresponding to inner layer
 12 of Figure 2 and identical with inner layer 11 referred
 to above.

The above layers were assembled on a drum with frictioned and skinned surfaces toward the center of the sleeve in the order given and wrapped, vulcanized, and cut in the manner described to form a plurality of check straps 9 inches long, $\frac{1}{2}$ inch wide, and $\frac{1}{4}$ inch thick. These individual check straps were then placed between the heated platens of a simple hand-operated press where their edge surfaces were heat sealed by the fusion of the nylon of the fabric and longitudinal cords exposed at these edges and in contact with the platens which were heated to a temperature of 480° F.

Check straps according to this invention, having their edge surfaces protected by a thin coating of fused nylon, are particularly desirable for use in multiple groups of 3 or 4 straps as shown in the checking mechanism illustrated in Figures 3 and 4. The individual straps 19, 19a and 19b are in a horizontally disposed position in superimposed relation so that each may act independently in checking the motion of the picker stick 20 carrying the loom picker 21 which will operate back and forth within the strap as the throw of the shuttle is halted and then thrown in a reverse direction.

Although the multiple check straps will operate independently they will be contiguously superimposed and will rub against each other along their edge surfaces. These straps will be primarily restrained, however, by the operation of the depending snubbing fingers such as 22 and 22a which are mounted upon the loom table 25 in a fixed position. These particular fingers are so arranged that they will contact the inner periphery of the check straps and in order that they may exert the desired force against this inner periphery of the straps, additional snubbing fingers 23 and 23a are provided to engage the strap about their exterior periphery at a point midway between the interior fingers. These exteriorly located fingers such as 23 and 23a are preferably mounted upon a horizontally disposed lug 24 which is provided with a slot to allow the lateral adjustment of the snubbing fingers 23 and 23a so as to control the force which they will exert upon the exterior surface of the strap.

It is to be understood that these check straps may also be used as individual wide bands between snubbers in the manner shown, for example, by Patent No. 1,341,941 or No. 2,393,148.

By the use of the inner and outer surface layers of the nylon fabric referred to, applicant has been enabled to produce check straps giving substantially improved performance over check straps made using cotton and the like, as was the prior practice. The outer surface of the nylon-cotton fabric which is in contact with the snubbers and with the stick is preferably free from rubber. The resulting construction has been found to give the proper coefficient of friction and degree of drag in a checking mechanism of the type in which snubbers are used as described in the art referred to above. This results in proper positioning of the looms. Furthermore, the coefficient of friction must not change with age or wear, and this has been found to be the case in the construction of the present invention.

In preparing the cushioning layer described herein, or in rubberizing the fabric or cords, either natural or synthetic rubber as well known to the art may be used. The term "rubber" as used herein is intended and does include natural rubber as well as the synthetic rubber-like and vulcanizable elastic materials known as synthetic rubber, including the rubber-like conjugated butadiene hydrocarbon polymers and copolymers with styrene, ac-

rylonitrile or other monomers copolymerizable therewith containing an active $\text{CH}_2=\text{C}<$ group, the halogenated di-olefin polymers of the chloroprene type known as neoprene, the polysulfide rubbers of the thiokol type, and the isobutylene-diolefin copolymers of the butyl rubber type.

While the foregoing structure has been described in connection with a continuous annular member, it may also be utilized in the fabrication of check straps of other types, for example, a non-endless type where the strap is fastened at both ends to the loom in the manner set forth, for example by Patent No. 2,291,587, or the like.

I claim:

1. A loom check strap comprising a laminated rubber and fabric annular body the outermost layers of which are of nylon containing fabric, a centrally positioned layer of longitudinally arranged nylon-containing reinforcing cords and a thin coating of fused nylon about the edge portions of said body.
2. A check strap construction according to claim 1 wherein the nylon containing fabric contains at least 50 percent nylon and at least 10 percent cotton.
3. A check strap construction according to claim 1 wherein the nylon containing fabric contains approximately 75 percent nylon in the form of cut staple and 25 percent cotton.
4. A check strap construction according to claim 3 wherein the nylon fabric in the outer surface layers is bias laid.
5. A loom check strap comprising a laminated rubber and fabric body, a centrally positioned layer of longitudinally arranged nylon-containing reinforcing cords and a thin coating of fused nylon about the edge portions of said body.
- 35 6. A loom check strap comprising superimposed laminae of rubber and of fabric at least some of which are nylon-containing and a thin coating of fused nylon about the edge portions of said body.
7. A loom check strap comprising a laminated rubber and fabric body the outermost layers of which are of fabric and a thin coating of fused nylon about the edge portions of said body.
- 40 8. A method for the manufacture of loom check straps comprising forming a cylindrical sleeve of rubber and nylon-containing fabric layers, cutting individual straps from said sleeve and subjecting the cut edges to elevated temperatures to fuse the nylon at the exposed edges of said fabric layers, and spreading said fused nylon over the cut edges of the straps.
- 45 9. A method for the manufacture of loom check straps comprising forming a cylindrical sleeve of rubber and nylon-containing fabric layers, cutting individual straps from said sleeve and subjecting the cut edges to heated platens the temperature of which is above the melting point of the nylon, whereby fusion of the nylon at the exposed edges occurs, and spreading said fused nylon over the cut surfaces of said straps.
- 50 10. A method for the manufacture of loom check straps comprising forming a body of rubber and of nylon-containing laminae, subjecting the edges of said body to elevated temperatures to fuse the nylon at the edges of said laminae, and spreading said fused nylon over the edges of said body.
- 55 11. A method for the manufacture of loom check straps comprising forming a body of laminated rubber and fabric layers and spreading a coating of fused nylon over the edges of said body.
